UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

BUTTONING-MACHINE.

1,207,729.

Specification of Letters Patent. Patented Dec. 12, 1916.

Application filed January 2, 1915. Serial No. 265.

To all whom it may concern:

Be it known that I, HERBERT E. ENSLIN, a citizen of the United States, residing at Malden, in the county of Middlesex and 5 State of Massachusetts, have invented certain Improvements in Buttoning-Machines, of which the following description, in connection with the accompanying drawings, is a specification, like reference characters on 10 the drawings indicating like parts in the several figures.

This invention relates to buttoning machines and the general object of the invention is to provide a machine by the use of 15 which buttoning operations may be performed quickly and satisfactorily.

In the manufacture of button boots and shoes, it is the usual practice to button at least three or four and frequently more of 20 the lower buttons of an upper preparatory to the assembling and lasting operations, in order to hold the button piece and buttonhole fly of the upper positioned correctly with 25 relation to each other to permit the upper to be fitted properly to a last and the shoe to be lasted properly.

Prior to the invention set forth in my co-pending application Serial No. 719,979, filed Sept. 12, 1912, the above mentioned buttoning operation was universally performed by hand. By that invention, however, a machine was provided which is capable of performing this buttoning operation much more 30 quickly and satisfactorily than it is possible to perform it by hand, since the machine disclosed in my said application is organized to button at one operation of the machine and substantially simultaneously as many buttons as it is desired to button on 35 a given upper, and also because of the accuracy and rapidity with which it buttons each button, and by reason of the facility with which it can be used to operate upon work of different styles and sizes.

40 A specific object of the present invention is to improve the machine disclosed in said application without sacrificing any of the above mentioned and other features and advantages characteristic of that machine, to 45 the end that a machine may be produced by the use of which the performance of the

above mentioned buttoning operation may be still further facilitated and which will be adapted for a greater variety of work.

Accordingly, the present invention is herein shown and described as embodied in a machine of the type disclosed in said co-pending application. It is to be understood, however, that it is contemplated that the invention as a whole or various features thereof 55 of may have many and widely different uses, including application to buttoning machines of other types.

One of the features of the machine herein shown and described as illustrating a preferred embodiment of the present invention 60 consists in a novel construction and arrangement of the buttoning means for dividing the operation of buttoning each button into two steps to dispose the two sides of each button-hole successively in buttoned relation to the corresponding button. This construction and mode of operation are well adapted for all kinds of work and at the same time especially adapted for use in connection with 65 uppers having buttonhole flies of heavy or unyielding stock or buttonholes which are relatively short in proportion to the size of the heads of the buttons. Still further to facilitate the performance of buttoning operations, the illustrated machine includes 70 novel means for effecting a preliminary movement of each of the sides of a button-hole whereby they are carried substantially to the edge of the head of the corresponding 75 button prior to their disposition under the head of the button in buttoned position. To prevent displacement of the buttoning members by reason of these preliminary movements of the sides of the buttonholes, in accordance with a further feature of the invention, the illustrated buttoning members are provided with extensions arranged to enter and engage the sides of the buttonholes.

Other features of the invention reside 80 in the construction, arrangement and mode of operation of the buttoning means including a hinged construction of the buttoning members to prevent excessive strains 85 upon those members.

100 Another of the features of the invention consists in novel means for imparting a

positioning movement to the work preparatory to a buttoning operation. In the illustrated embodiment of the invention, this means comprises jaws arranged to seize 5 a button piece and impart to it a button positioning movement relatively to the work receiving means, the jaws thereafter holding the button piece against accidental displacement of the buttons.

10 Still other features of the invention will be apparent from the following detailed description read in connection with the drawings and the various novel features of the invention will then be set forth in the appended claims.

Referring to the drawings: Figure 1 is an angular perspective looking at the front of a machine embodying the present invention and showing the various operating instrumentalities of the machine in their initial positions; Fig. 2 is a central longitudinal vertical section; Figs. 3, 4 and 5 are side elevations illustrating the relative locations of the various operating instrumentalities of 20 one set in successive selected positions; Fig. 6 is a detail in perspective of parts shown in Fig. 5 in the same positions of the parts; Fig. 7 is a detail in elevation showing the positions of the buttoning members when one side of a buttonhole has been disposed in buttoned position; Fig. 8 is a perspective detail showing the parts in the positions shown in Fig. 7; Fig. 9 is a perspective view similar to Fig. 8 showing the positions 25 of the buttoning members at the conclusion of a buttoning operation; Fig. 10 is an angular perspective of one of the end button holders taken from below; Fig. 11 is an angular perspective detail showing the 30 mounting of the members which carry the work receiving and button eye supporting devices; Fig. 12 is an angular perspective of a pair of buttonhole spreaders; Fig. 13 is an angular perspective taken from below 35 looking toward the rear of the machine and showing the means for unlocking the work receiving and button eye supporting means to permit their removal from the machine; Fig. 14 is an angular perspective of the 40 work seizing and positioning jaws; Fig. 15 is an angular perspective detail of the lower member of said jaws; Fig. 16 is a vertical section showing in detail the construction and arrangement of a button head engaging 45 plunger and associated buttoning members; Fig. 17 is a perspective detail of the means for locking a button head engaging plunger in its carrying sleeve; Fig. 18 is an angular perspective in elevation of one of 50 the buttoning members; Figs. 19 and 20 are perspective details of the lower part of a buttoning member taken from different view points; Fig. 21 is a vertical section of the lower part of a specially fitted button head engaging plunger; Fig. 22 shows a 55

button of a particular type; and Fig. 23 is a plan view showing a series of button holders constructed to be especially adapted for handling buttons attached in a particular manner.

As above stated, the machine herein shown and described for the purpose of illustrating a preferred embodiment of the present invention, is a machine of the type disclosed in my said co-pending application. Conveniently, and as shown, except as hereinafter fully explained and described in detail, the machine may be constructed like or substantially like the machine illustrated in said co-pending application and reference should be had to the specification and drawings of said co-pending application for detailed exposition of features and details of construction and operation not fully explained and described herein.

The illustrated machine, as hereinbefore stated, is designed to permit the presentation thereto of work provided with a plurality of buttons and buttonholes and to perform theron during one operation of 90 the machine and substantially simultaneously, a plurality of buttoning operations, the operation of completely buttoning a single button being usually herein termed a buttoning operation. For buttoning each 95 button, the illustrated machine has a set of operating instrumentalities comprising work receiving means and means for taking the work from the receiving means and performing a buttoning operation. As 100 shown, the machine has seven such sets of operating instrumentalities, although obviously the number of sets may be greater or less as desired, the illustrated machine being equipped with the above stated number of 105 sets because, in practice, seven buttons is usually the greatest number which it is desired to button on a single upper.

For receiving the work from the operator and presenting it to the buttoning instrumentalities, the machine is provided with a series of horizontally disposed button receiving and positioning forks 2, (Fig. 1) commonly herein termed button holders, and a series of buttonhole fly receiving members, 115 usually herein termed fly holders, comprising a plurality of horizontally disposed forks 4 positioned above the button receiving forks 2 and having associated therewith a corresponding number of buttonhole 120 spreaders 6. To prevent catching in the outer or end buttonholes of the series of buttonholes to be operated upon during the introduction of the work into the fly holders, each of the outer forks 4, as shown, has 125 only one prong (Fig. 1), the outer members 4 being nevertheless for convenience generally herein referred to as forks as well as the intermediate and forked members 4.

Each of the button receiving forks 2 com- 130

prises a pair of arms 8 and 10 forming an open mouthed slot 12. As shown, the two outer button receiving forks 2 are each provided with a pair of spring fingers 14, best 5 shown in Fig. 10, formed to allow the eyes of the two outer buttons of the series of buttons to be operated upon to be passed inwardly between and beyond the adjacent portions of said fingers and to retain said 10 button eyes yieldingly against accidental displacement of said buttons from the end button forks, thus holding the series of buttons as a whole from becoming accidentally dislodged from the button receiving forks. 15 Conveniently, the spring fingers 14 may be formed of wire bent, for example, as shown in Fig. 10, the rear ends of the wire fingers 14 being received in grooves channeled in the top faces of tie plates 16 pinned to the 20 under sides of the end button forks 2. Preferably, too, the arms 8 and 10 of the button receiving forks 2 are beveled around their inner faces as shown at 18 (Fig. 10) to prevent cutting or fraying the button attaching threads as the buttons are introduced 25 into the button receiving forks. Advantageously, also, and as shown, the spring fingers 14 carried by the end forks 2 may be beveled on their under sides at and near 30 their front ends as indicated at 20 and the under faces of the front ends of the arms of the several forks 2 may be similarly beveled, as indicated at 22, (Fig. 10) to facilitates straightening the buttons into upright 35 position as they are introduced into the button receiving forks.

In the use of the above-described button receiving forks 2, the eyes of the buttons are received in and stand in the slots 12, the 40 buttons being held upright in the said forks by reason of the flat bottoms of the button heads resting upon the upper faces of the arms 8 and 10 of the forks 2, (Fig. 3) and the eyes of the end buttons being forced 45 between the spring fingers 14 and held yieldingly by those fingers against accidental movement from said end forks.

Each of the button forks 2 is carried at the front end of a slide bar 24, the slide bars 50 24 passing through and being supported in guides 26 (see Figs. 2 and 11) and secured at their rear ends for reciprocating movement with a slide 28 (Fig. 2) traveling on shelves 41 (Fig. 2) projecting from the side 55 walls of the machine frame and arranged to be operated to reciprocate the slide bars 24 and button holders 2 by a cam 29 on the main shaft 30 through a link 31 and a lever 32 fulcrumed on a cross shaft 33 supported 60 by the machine frame, said lever 32 carrying a roll 34 for engaging said cam 29.

To adapt the machine especially for receiving and properly positioning buttons attached in such a manner that the buttons 65 are presented to the button receiving forks

2 with the eyes of the buttons extending crosswise of the positioning slots formed by the arms of said forks, whenever it is desired to operate upon buttons so attached, the button receiving forks 2 may be constructed and arranged, as shown in Fig. 23, wherein each of the button receiving forks 2 is shown with the inside face of its outer arm curved to provide a cam face 36 and shaped at its mouth to be wide enough to 70 receive a button presented with its eye extending transversely of the fork, the cam face 36 operating to turn the button as it is moved into the fork to direct the eye of the button lengthwise of the fork in position 75 80 to be received in the relatively narrow portion of the slot 12 for presentation to the buttoning means.

The buttonhole fly holders 4, as illustrated, are mounted and operated in substantially the same manner as the button receiving forks 2, the fly holders 4 being formed on the front ends of slide bars 38 which pass through and are supported in the guides 26 (Figs. 2 and 11), each buttonhole fly holder slide bar 38 resting upon a corresponding button holder slide bar 24. The rear ends of the slide bars 38 are operatively connected for horizontal reciprocating movement with a slide 40 guided at its 95 ends between shelves 25 and brackets 27 (Fig. 13) secured to the side walls of the machine frame and connected by a link 42 with a lever 43 fulcrumed on the shaft 33 and carrying a roll 44 engaging a cam 45 100 on the main shaft 30.

The buttonhole spreaders 6 for each set comprise a pair of horizontally disposed spreader arms 46 (Fig. 12) located below the buttonhole fly supporting forks 4 and pivoted for opening and closing movement at 47 in a shell 48. Each shell 48 is pivotally connected at 50 to the corresponding fly holder slide bar 38 for movement with the associated fly holder 4 lengthwise of the 110 machine. Each spreader arm 46 carries at its front end an upstanding blade 52 adapted to enter a buttonhole. To maintain the spreader arms 46 and the spreader blades 52 normally together in the closed position 115 of the spreaders, springs 54 (Fig. 12) are disposed between the rear ends of the spreader arms of each set.

In the use of the machine, the buttonhole fly is initially positioned so that it rests 120 upon and is supported by the buttonhole fly receiving forks 4 and the spreader blades 52 project upwardly through the buttonholes (Fig. 3).

For convenience in introducing the work, 125 the fly holders 4 and spreaders 6 in their initial positions project forwardly away from the machine in front of the buttoning means, as shown, for example, in Figs. 1 and 2, the term work for convenience being va- 130

riously used in this specification and the appended claims in a broad sense to designate whatever is handled or operated upon by any of the instrumentalities of the machine such, for example, as the upper as a whole, the buttonhole fly or button piece, or both, or the buttons attached to the upper. Similarly, the outer ends of the button receiving forks 2 are normally substantially in line with the buttonhole fly holders 4, as clearly shown, for example, in Fig. 2.

During the first part of the operation of the machine, the fly holders 4 and spreaders 6 are moved backwardly toward the machine to position the buttonholes for the action of the buttoning means (Fig. 4), the spreader blades 52 preventing accidental disengagement of the fly from the fly holders during this movement. During this backward movement of the fly holders 4, the spreader arms 46 are forced apart by sliding engagement with projections 53 on the shanks of the button holders 2 and normally standing in slots 55 (Fig. 12) formed by recesses in the adjacent faces of the two spreader arms 46 of each pair. This causes the spreader blades 52 to act upon opposite sides of each of the buttonholes to spread the buttonholes and hold them open to facilitate the entrance therein of the button head engaging means.

For swinging the shells 48 about their pivots 50 to lower the spreaders out of the buttonholes after the buttonholes have been entered by the button head engaging means and thus positioned for the buttoning operations, the shells 48 are provided with extensions 56 adapted to ride over inclined faces 58 on the button holder slide bars 24. The construction is such that, after the buttonholes have been presented to and entered by the button head engaging means, the fly holder slide bars 38 are given a backward movement while the button holder slide bars 24 remain stationary with the result that the extensions 56 on the shells 48 are caused to ride upwardly over the inclined faces 58 on the slide bars 24 against the resistance of spring pressed plungers 60 engaging the shells 48, thus tipping the shells 48 in a direction to lower the spreaders from the buttonholes, continued backward movement of the fly holder slide bars 38 carrying the fly holders 4 and spreaders 6 into an inoperative position shown in Fig. 5.

As above stated, in addition to the work receiving means each set includes means for taking the work from the receiving means and performing a buttoning operation. For taking the work from the receiving means and positioning the buttons and buttonholes for the buttoning operations, each set has a vertically disposed button head engaging plunger 62 and an opposed coöperating but-

ton eye supporting anvil 64, the said plunger and the said anvil being arranged for movement into position to hold a button between them upon presentation of the button by the work receiving means.

Each plunger 62 comprises a work engaging portion 65 (Fig. 16) and a stem 66 adjustably supported in a sleeve 68 by means of an adjusting nut 70, the adjusting nut 70 of each set having threaded through it 75 a tapered pin 74 (Figs. 16 and 17) for the reception of which the upper end 75 of the corresponding plunger stem 66 is drilled and split as shown in Fig. 17. The tapered pins 74 expand the tops 75 of the plunger stems 66 by wedging engagement therewith and securely lock the plunger stems in adjusted positions in the sleeves 68. Each plunger 62 is spring pressed toward the work by a rather stiff coil spring 76 (Fig. 80 16) seated between a shoulder 78 on the plunger 62 and a shoulder 80 on the inside face of the sleeve 68. The button head engaging faces 81 of the plungers 62 are preferably cupped, as indicated in Fig. 16, to 85 cause each of them to conform approximately to the contour of the crown of a button head and, to provide for operating for example, upon buttons of the type illustrated in Fig. 22, the cupped ends of the 90 plungers 62 have central recesses 83 (Fig. 16) adapted for the reception of the projecting portions 85 of the said buttons. As shown in Fig. 21, the work engaging end 95 face 81 of each plunger 62 may be bored lengthwise of the plunger to receive a plug 82 slidably secured to the plunger by a headed rod 84 and normally pressed outwardly by a spring 86, each plug 82 normally projecting slightly beyond the plunger end and yielding upon engagement with the head of a button as much as may be necessary to cause the plunger to conform to the shape of the crown of the button head.

The plunger carrying sleeves 68 are supported in holders 90 (Figs. 1 and 2) by means of the nuts 72 which are threaded on the sleeves 68 at their upper ends and rest upon the upper faces of the holders 90. The sleeve holders 90 are mounted for movement 100 with a reciprocating head 92 guided on vertical ways on the machine frame and arranged to be operated to lower and raise the plungers 62 and associated parts toward and from the work by means of a bell crank, indicated generally at 94 (Fig. 2), fulcrumed on a shaft 96 supported by the machine frame, the bell crank 94 having two forwardly extending arms, one of which is shown at 98 (Fig. 2), slidably pivoted at 105 95 to each end of the head 92, and a rearwardly extending arm 98 carrying a roll 99 arranged to engage a cam 100 on the main shaft 30.

The anvils 64 comprise upstanding blocks 110

having flat top work engaging faces preferably roughened or corrugated as shown in Fig. 1 to facilitate firm engagement with the work, each anvil 64 being in vertical alignment with the corresponding plunger 62. The anvils 64 are adjustably secured to the front ends of bars 102 by screws 103 (Fig. 3) received in slots 105 (Figs. 1 and 3) in the front ends of the bars 102, this construction providing for adjustment of the anvils lengthwise of the machine to vary the line or curve of the anvils according to the line or curve of the buttons and button-holes. Each of the anvil bars 102 extends through the lower part of one of the guides 26 (Figs. 2 and 11). At its rear end each anvil bar 102 engages a cross rod 104 (Figs. 2 and 13) supported at its ends for turning movement in the machine frame. To permit the anvil bars 102 to be readily removed from the machine and at the same time to provide for locking them in the machine when in use, the cross rod 104 has two opposite flattened sides and each of the anvil bars 102 is split at its rear end and provided with a slot (Fig. 2) adapted to receive the cross rod 104 in one position thereof and so shaped that when the cross rod is turned in the slots in the anvil bars into the position shown in Fig. 2, each anvil bar 102 is securely locked in engagement with said cross rod.

To provide for turning the rod 104 to unlock the anvil bars 102 to permit one or more of them to be removed from the machine as desired and at the same time to provide for securing the rod 104 in position to lock the anvil bars 102 in the machine, the said rod 104 extends at its ends outwardly beyond the outer faces of the side walls of the machine frame and is provided at one end with a check nut and at the other end with a handle 106 and a locking pin 107 (Fig. 13) adapted to be dropped into a recess in the outer face of the adjacent side wall of the frame. Preferably, the rod 104 is connected with means for unlocking the button and fly holder bars 24, 38 so that, upon turning the rod 104, as many of the button and fly holders as may be desired may be conveniently removed from the machine. To this end, the slide 28 to which, as above stated, the button holder bars 24 are secured for horizontal reciprocating movement, is formed in two parts pivotally connected to allow downward swinging movement of one of these parts relatively to the other. As shown, the rear part of the slide 28 near one end has integral therewith a depending lug 108 (Fig. 13), while the front part of the slide 28 has secured to its under side a lug 110 pivotally connected to the lug 108 by a screw 112 passing freely through the lug 108 and threaded into the lug 110. To effect downward swinging

movement of the front part of the slide 28 about its pivotal connection with the rear part of said slide, the rod 104 carries a split clamp 114 secured to the rod 104 for turning movement therewith by a screw 116 and having an upwardly extending portion which carries a pin 118 arranged upon movement toward the slide 28 to enter a forked end 120 of the lug 110. Upon continued turning movement of the rod 104, the pin 118 swings the front part of the slide 28 downwardly far enough to clear the rolls 122 by which the button holder bars 24 are secured to the slide 28 for horizontal movement therewith. This permits the button holder bars 24 to be freely removed from the machine, after which the corresponding fly holder bars 38 may be similarly removed by lowering them until the rolls 124 by which the fly holder bars 38 are secured to the slide 40 have cleared the under face of that slide. To maintain the front part of the slide 28 normally in its raised position, the screw 112 has wound around it a spring 126 the rear end of which engages the under face of the rear part of the slide 28 and the front end of which engages the under face of the front part of the slide 28. The opposite end of the front part of the slide 28 is similarly pivotally mounted and normally spring supported, as shown in Fig. 2.

In order that the anvils 64 may be raised and lowered toward and from the work, the anvil bars 102 intermediate between their ends rest upon a cross bar 128 (Figs. 1 and 2) secured for vertical adjustment of the anvil bars 102 and anvils 64 by set and binding screws, one of which is shown at 130 (Fig. 2), to the cross bar 132 of a yoke 134 fulcrumed for swinging movement upwardly and downwardly to raise and lower the anvil bars 102 and anvils 64 on a shaft 136 extending transversely of the machine and supported in the machine frame. A tie rod 138 (Figs. 1 and 2) straddles the anvil bars 102 and secures them to the cross bar 128 for movement with the yoke 134. The yoke 134 is operated by a heavy toggle comprising links 140, 142 pivoted together at 143. The link 140 is pivoted to the yoke 134 at 144 (Fig. 2) and the link 142 is fixed at its lower end to a rock shaft 146 (Figs. 1 and 2) mounted in bearings in the machine frame and carrying fixed to it near its outer end a link 148 (Fig. 1) pivoted to an operating rod 150 pivotally supported at its rear end by a link 152 (Fig. 2) pivoted on the shaft 33 and carrying a roll 154 arranged to engage a cam 156 on the main shaft 30. In the normal positions of the parts, the toggle 140, 142 is broken, as shown in Fig. 2, and the anvils 64 are positioned below their work engaging position. Upon movement of the operating rod 150 to straighten the toggle 140, 142, the yoke 134 is moved

upwardly to carry the anvils 64 into position to support the eyes of the buttons. An advantage of the toggle construction described is that, in the straightened position 5 of the toggle, the toggle forms a solid, rigid support for holding the anvils very securely in their operative position.

To align the buttons with the plungers 62, the illustrated machine is provided with a 10 pair of relatively movable jaws arranged to be closed to seize the button piece and impart to it a movement backwardly to draw the buttons into the button forks 2 and position and hold the buttons positioned in the said 15 forks in line with the plungers 62. These jaws comprise an upper jaw 158 carried at the front end of a supporting bar 160 and a lower jaw 162 carried at the front end of a rod 164 pivoted at 166 to the bar 160 20 (Figs. 2, 14 and 15). The jaw supporting bar 160 passes through and is supported in the center guide 26 between the center button holder bar 24 and the center anvil bar 102. The rear end of the bar 160 is slotted 25 to receive a bent rod 168 (Figs. 2 and 14) having an upwardly extending front end 169, upon which the bar 160 is hung. A rearwardly extending rod 170, secured to the rod 168 in an offset position by a tie 30 piece 172, slides in a bearing 174 (Fig. 2) carried on the shaft 136. The described construction permits ready detachment of the jaws 158, 162 from the machine by lifting the bar 160 from the upwardly extending 35 part 169 of the bent rod 168 when permitted by prior removal of the button holder bars 24.

Conveniently, the button piece engaging jaws 158, 162 are arranged for movement 40 with the fly holders 4 so that, as the fly holders are drawn backwardly to position the buttonholes in line with the plungers 62, the jaws 158, 162 are moved backwardly to position the buttons in the button holders 2 in 45 line with the buttonholes and plungers 62. In order that the jaws 158, 162 may be thus operated with the fly holders 4, the tie piece 172 is pivotally connected at 176 to a link 178 (Fig. 2) the rear end of which link is 50 pivoted at 180 to the lever 43 which operates the fly holder bars 38.

To provide for closing the button piece gripping jaws 158, 162 in engagement with the button piece, in the illustrated construction, the lower jaw 162 is provided with spaced depending extensions 182 (Fig. 15) arranged to straddle the center anvil bar 102 and to rest on the anvil bars 102 at either 55 side of the center anvil bar. The said anvil bars 102 upon which the extensions 182 of the lower jaw 162 rest have secured to their top faces, by means of adjusting screws 184 and binding screws 186 (Figs. 2 and 3), cam blocks 188, upon which the extensions 182 60 of the lower jaw 162 ride, the construction

being such that during the first part of the backward buttonhole positioning movement of the fly holders 4, the said extensions of the lower jaw 162 are caused to ride upwardly upon the cam blocks 188 to close the 70 jaws in engagement with the button piece, while on continued backward movement of the fly holders 4, the button piece is drawn backwardly to align the buttons with the corresponding buttonholes and plungers 62 75 (Fig. 4).

The upper jaw 158 preferably carries an abutment plate 190 (Fig. 14) spaced from and secured to the jaw 158 by strips 192. In the introduction of the work into 80 the machine, the eyes of the buttons are thrust against the front face of the abutment plate 190 and held there by the operator until the jaws 158, 162 close upon the button piece. Preferably, the lower jaw 162 85 comprises a spring bar 194 (Fig. 15) carrying at its ends transverse work engaging plates 196 having their upper and work engaging faces roughened or corrugated to give them a sufficiently firm grip upon the work. 90 The spring construction of the lower jaw 162 gives it a considerable adaptability to button piece stock of different thicknesses, while the above-mentioned screws 184 for effecting vertical adjustment of the cam 95 blocks 188 provide for determining the extent of closing movement of the jaws, thus further adapting them for work of different thicknesses.

After the buttons and buttonholes have 100 been brought into alignment with the plungers 62 through backward movement of the fly holders 4, as above described, the plungers 62 are lowered by downward movement of the head 92 and caused to enter the buttonholes. Thereafter the spreader blades 52 are swung downwardly out of the buttonholes and the fly holders 4 and spreaders 6 are withdrawn to an inoperative position in the rear of the plungers 62. Upon continued downward movement of the head 92 105 the plungers 62 are lowered into engagement with the crowns of the button heads and the anvils 64 are raised, through upward movement of the yoke 134 upon 110 straightening of the toggle 140, 142 through the rod 150 and cam 156, into engagement with the lower side of the button piece in position to support the eyes of the buttons in opposition to the plungers 62. The button holders 2 are then withdrawn backwardly to an inoperative position. Thereafter, while the buttons are thus held 115 against translation between the plungers 62 and anvils 64 and the buttonholes are held 120 positioned in alignment with the heads of the buttons by the plungers 62, each buttonhole is disposed in buttoned relation to the corresponding button by buttonhole fly 125 engaging means comprising for each set a pair 130

of relatively movable buttoning members 200, 202, for convenience herein usually termed tuckers and preferably made of spring material. These buttoning members 5 200, 202 are arranged to be moved with the plungers 62 upon movement of the head 92 to bring the plungers into engagement with the heads of the buttons and thereafter to have relative movements first independently 10 of the head 92 and then with the head 92 to dispose first one and then the other side of each buttonhole in buttoned position.

Each tucker 200 is pinned at 204 and 206 (Fig. 16) to a plate 208 integral with or 15 fixed to a rod 210 slidably mounted in a vertical slot 212 in a forward extension of the corresponding plunger sleeve 68. The lower end of each tucker carrying rod 210 is cushioned against a spring 214 seated in 20 an extension of the slot 212 and serving as a return spring to raise the said tucker 200 to its normal inoperative position when permitted. Each tucker 202 is pinned through a hole 216 (Fig. 18) to the outer face of the 25 said extension of the sleeve 68 on the other side of the said sleeve and directly opposite the plate 208, each tucker 202, in consequence of its said mounting, being always movable with its sleeve 68 upon movement of the 30 cross head 92.

For imparting to each tucker 200 a buttoning movement relatively to its sleeve 68 and the opposed tucker 202 while said parts remain stationary, the illustrated machine is 35 provided with an auxiliary cross head 218 (Figs. 1 and 2) normally engaging the top faces of heads 220 on the upper ends of the rods 210, the heads 220 being integral with said rods or, as shown, in the form of split 40 clamps pinned to said rods. To provide for reciprocation of the auxiliary cross head 218, the said cross head is carried at the front ends of two forwardly extending levers 222, 224, (Fig. 1), each of which is fulcrumed at 45 95 (Fig. 2) and connected at its rear end to a forwardly extending arm of a bell crank 226 fulcrumed on the shaft 96 and having a single rearwardly extending arm 228 carrying a roll 230 in the path of a cam 232 on the main shaft 30, the rear ends of the levers 222, 224 being slotted to receive blocks 233 50 on pivot pins 235 carried by the said forwardly extending arms of the bell crank 226.

In the operation of the machine, the tuckers 55 200 and 202, by reason of their above-described mounting, are carried downwardly with the plunger carrying sleeves 68 upon downward movement of the head 92 to bring the plungers 62 into engagement with the heads of the buttons. After the plungers 62 have engaged the heads of the buttons and the anvils 64 have been moved upwardly so that the buttons are clamped between the 60 plungers 62 and the anvils 64 and the fly 65 holders 4 and button holders 2 have been

moved backwardly into inoperative positions, a downward movement of the auxiliary head 218 is effected while the main head 92 remains stationary. During this downward movement of the auxiliary head 218, 70 the tuckers 200 are forced downwardly, relatively to their carrying sleeves 68 and the tuckers 202, to force one side of each buttonhole over the adjacent portion of the edge of the corresponding button head and 75 under the button head in buttoned position by engagement of the said tuckers 200 with the buttonhole edge binding stitches on the top face of the buttonhole fly. Thereafter, a further downward movement of the main 80 head 92 is effected. During this movement of the head 92, the plungers 62 remain stationary by reason of their engagement with the heads of the buttons the eyes of which are rigidly upheld by the anvils 64, while the 85 plunger carrying sleeves 68 move downwardly against the tension of the springs 76. This downward movement of the sleeves 68 carries the tuckers 202 downwardly relatively to the tuckers 200 to force the other 90 side of each buttonhole over the edge of the corresponding button head and dispose it in buttoned relation under the button head by engagement with the buttonhole edge binding stitches on the top face of the buttonhole fly 95 at that side of the buttonhole, in the same manner that the first side of each buttonhole was carried into buttoned position by the tuckers 200, thus completing the buttoning of each button.

To facilitate the buttoning action of the tuckers 200 and 202, they are preferably formed at their lower ends (as best shown in Figs. 18 to 20) to conform substantially to the contour of the heads of the buttons and 105 to tuck the stock on the two sides of each buttonhole under the head of the adjacent button and then to crowd the said stock snugly against the eye of the button, each of the tuckers 200, 202 being provided with in-turned ends indicated at 234 (Figs. 18 and 19) and these in-turned ends and the portions of the tuckers adjacent thereto being curved to conform substantially to the curvature of the edge of a button head, as clearly 110 shown in Fig. 19.

To facilitate forcing the sides of each buttonhole over the edge of the corresponding button head, each of the illustrated tuckers 200, 202 is provided with an inwardly extending projection providing a cam face 236 (Fig. 19) arranged to lie in a slot 238 (Fig. 16) formed in the adjacent face of the corresponding plunger 62, each slot 238 having a raised hump indicated at 240 (Fig. 16) 120 upon which the cam face 236 of the adjacent tucker 200, 202 rides during the first part of the buttoning movement of that tucker, with the result that each tucker is thereby 125 given a preliminary outward movement to- 130

ward the peripheral edge of the button head to carry the adjacent side of the buttonhole outwardly to the edge of the button before the tucker operates to force it over the said edge. To insure that each tucker will carry the side of the buttonhole being operated upon to the edge of the button head without slipping off the edge binding stitches, each tucker 200, 202, is formed with a depending spur 242 arranged to enter and engage a side of the buttonhole. To facilitate the entrance of the spurs 242 into the buttonholes, each spur 242 is preferably wedge shaped with a straight inside face and an inclined outside face, as clearly shown in Figs. 19 and 20.

To lessen the strain upon the tuckers 200 and 202 during the operation thereof, preferably each tucker is made in two parts, the shank part having a bifurcated lower end 244 formed to receive a tongue 246 projecting upwardly from the work engaging part (Fig. 18), the shank part and the work engaging part of each tucker being hinged together by a pivot pin 248 passing through the bifurcated end 244 of the shank part and the tongue 246 of the work engaging part. A spring 250 pinned at 252 (Fig. 3) to a part of the associated plunger carrying sleeve 68 has an arm overlying the work engaging part of each tucker 200, 202, the springs 250 pressing the work engaging parts of the tuckers of each pair inwardly toward each other and the intermediate plunger 62.

After the completion of the buttoning operations, the heads 92 and 218 are raised and the anvil yoke 134 is swung downwardly to release the work from the plungers, tuckers and anvils, the parts being finally restored to their initial positions.

In addition to the adjustments hereinbefore explained, the illustrated machine has provision for making a number of other adjustments of the operating instrumentalities.

To provide for adjusting the operating instrumentalities of the machine for operating upon differently spaced buttons and buttonholes, the several sets, except the center set, are arranged for simultaneous movement from and toward each other. To this end each of the guides 26, except the center guide 26, has a projection 251 standing in a slot extending transversely of the machine in a horizontal tie plate 253 (Fig. 11) fixed at either end to the machine frame, the said tie plate permitting sliding movement of the movable guides 26 along said slot and at the same time securing the guides 26 against movement lengthwise of the machine by engagement of said projections on the guides 26 with the walls of the slot in the tie plate. For effecting such sliding movement of the movable guides 26, the said

guides are connected by a system of toggles comprising a series of links 254 (Figs. 2 and 11) pivotally connected at their outer ends to cap plates 255 overlapping the tie plate 253 and pivoted at their inner ends to a lever 256 constituting a common central toggle link and fulcrumed on the fixed center guide 26, the toggle links 254 extending reversely on opposite sides of the center link 256. The common center link 256 at its forward end is connected to an arm 258 of a sliding controller 260 by a pin and slot connection. The controller 260 is operated by a bell crank 262 fulcrumed to the machine frame at 264. One arm of the bell crank 262 carries a horizontally disposed segmental gear engaging a companion gear carried by an arm 266 of a bell crank 268 fulcrumed on the machine frame at 270 and operated by a treadle rod indicated at 272. The controller 260 is connected with the holders 90 by a system of toggles like the toggles above described for connecting the controller with the movable guides 26 so that, upon movement of the treadle 272 and consequent movement of the controller 260, the several movable sets are moved as units to position their instrumentalities away from or toward each other to vary the spacing of the sets.

To provide for adjusting the plungers 62 and associated buttoning members 200, 202 according to the line or curve of the outer edge of the buttonhole fly and consequently the line or curve of the buttons and buttonholes, each of the holders 90, except the center holder, is pivoted at 274 to the head 92 for swinging movement about the said pivot 274, the lower portions of each of the holders 90 being provided with screws 276, 277 whereby the holders 90 may be adjusted about their said pivots and secured in adjusted positions. A corresponding adjustment of the button and fly holders may be effected by moving the slide bars 24 and 38 lengthwise of the machine relatively to their connections 122 and 124 with the slides 28 and 40, a like adjustment of the anvils 64 being provided for as above stated, by reason of their described adjustable mounting in the slots 105 in the front ends of the anvil bars 102.

To adjust the plungers 62 and associated buttoning members 200, 202 for buttonholes set in different angular positions, each sleeve 68 is provided near its top with an annular groove 278 (Fig. 16) adapted to be engaged by a screw 280 threaded through the sleeve 68.

The operation of the machine may be summarized as follows: The work is introduced into the machine as shown in Fig. 3 by placing the button eyes between the arms of the button receiving forks 2 and resting the heads of the buttons upon the said forks 130

2, the end buttons being inserted between the spring fingers 14 and the eyes of the buttons being pushed against the abutment plate 190. The buttonhole fly is then carried over and rested upon the fly holders 4, the buttonhole spreader blades 52 projecting upwardly through the buttonholes.

During the first part of the operation of the machine, the fly holders 4 are moved backwardly toward the machine to bring the buttonholes in alinement with the plungers 62 (Fig. 4), the spreader arms 46 being forced apart to cause the spreader blades 52 to open the buttonholes and hold them open for the passage therethrough of the plungers 62. This positioning movement of the fly holders 4 also pulls the jaws 158, 162 backwardly, causing the jaws to be closed to seize the button piece and then to impart to it a positioning movement to draw the buttons into the forks in alinement with the buttonholes and plungers 62. Thereafter, the plungers 62 are lowered by downward movement of the head 92 to cause the said plungers to enter the buttonholes. After the plungers 62 have entered the buttonholes, further backward movement of the fly holders 4 while the button holders 2 are held stationary, causes the buttonhole spreaders 6 to be swung downwardly to withdraw the spreader blades 52 from the buttonholes, still further backward movement of the fly holders 4 bringing the fly holders 4 and spreaders 6 into inoperative positions. Continued downward movement of the head 92 after the plungers 62 have entered the buttonholes lowers the plungers into engagement with the crowns of the button heads, the anvils 64 being moved upwardly to support the eyes of the buttons from below (Fig. 5). The button holders 2 are then withdrawn backwardly to an inoperative position whereupon downward movement of the auxiliary head 218 operates the tuckers 200 to carry one side of each buttonhole over the adjacent portion of the edge of the corresponding button head and dispose it in buttoned relation under the head of the button, the first part of this downward movement of the tuckers 200 carrying them into engagement with the buttonhole edge binding stitches on the top face of the buttonhole fly. Thereafter upon engagement of the cam faces 236 on the said tuckers with the coöperating cam faces 240 on the plungers 62, the tuckers 200 are moved outwardly to carry the sides of the buttonholes being operated upon to the peripheral edges of the button heads, the spurs 242 depending from the tuckers maintaining engagement of the said tuckers with the said edge binding stitches during this preliminary movement. Upon further movement of the auxiliary head 218, the tuckers 200 force the sides of the buttonholes over

the edges of the button heads, the inturned lip portions 234 tucking the stock snugly against the eyes of the buttons. Thereafter, upon movement of the head 92, the tuckers 202 are operated similarly to engage the second side of each buttonhole at its edge, to carry that side of each buttonhole outwardly to the peripheral edge of the button head, and then to crowd it over the edge of the head and dispose it in buttoned position under the head of the button. After the completion of the buttoning operations, the parts are restored to normal positions, the buttoned work being thereby released from the machine.

Having fully explained my invention and described in what manner the same may conveniently be embodied, what I claim as new and desire to secure by Letters Patent of the United States is:—

1. A buttoning machine comprising means for positioning a button, buttonhole fly engaging means, and operating mechanism constructed and arranged to effect relative movement of said button positioning means and said buttonhole fly engaging means in substantially the same manner with respect to the opposite sides of a buttonhole to dispose one side of the buttonhole under the edge of the button in buttoned relation thereto and thereafter similarly to dispose the other side of said buttonhole in said buttoned relation to the button.

2. A buttoning machine having, in combination, means for engaging a buttonhole fly, means for positioning a button, and mechanism constructed and arranged to effect relative movement of said fly engaging means and said button positioning means to render said fly engaging means effective successively at opposite sides of a buttonhole for disposing the material adjacent to the buttonhole in buttoned relation to the button.

3. A buttoning machine having, in combination, tuckers for engaging a buttonhole fly upon the two sides of a buttonhole, means for positioning a button, and mechanism constructed and arranged to effect relative movement of said tuckers and said button positioning means to cause the two sides of the buttonhole to be disposed successively in buttoned relation to the button.

4. A buttoning machine having, in combination, relatively movable tuckers for engaging a buttonhole fly upon the two sides of a buttonhole, means for positioning a button, and mechanism constructed and arranged to effect relative movement of said tuckers and said button positioning means to cause the two sides of the buttonhole to be disposed successively in buttoned relation to the button.

5. A buttoning machine having, in combination, tuckers for engaging a buttonhole

fly upon the two sides of a buttonhole, means for positioning a button, and mechanism constructed and arranged to effect relative movement of said tuckers to bring said tuckers successively into engagement with the buttonhole fly and by relative movement of said tuckers and said button positioning means to cause the two sides of the buttonhole to be successively disposed in buttoned relation to the button.

6. A buttoning machine having, in combination, means for positioning a button for a buttoning operation, buttonhole fly engaging means, and operating mechanism constructed and arranged to move said buttonhole fly engaging means to dispose one side of a buttonhole in buttoned relation to the button and thereafter to dispose the other side of said buttonhole in buttoned relation to said button.

7. A buttoning machine having, in combination, means for holding a button constructed and arranged to position a buttonhole also, buttonhole fly engaging means, and mechanism constructed and arranged to move said fly engaging means to dispose the two sides of said buttonhole successively in buttoned position under the head of the button.

8. A buttoning machine having, in combination, means for positioning a button for a buttoning operation, and means for carrying first one side of a buttonhole over the edge of the head of the button and then the other and successively disposing the two sides of the buttonhole in buttoned position under the head of the button.

9. A buttoning machine having, in combination, means for positioning a button for a buttoning operation, a pair of relatively movable buttonhole fly engaging members, and mechanism constructed and arranged to move one of said members to dispose one side of a buttonhole in buttoned position under the head of a button and thereafter to move the other of said members to dispose the other side of the buttonhole in buttoned position under the head of the button.

10. A buttoning machine having, in combination, means for positioning a button for a buttoning operation, a pair of relatively movable buttoning members constructed and arranged to engage the edge binding stitches on the two sides of a buttonhole, and mechanism operating to move one of said members to force the stock on one side of the buttonhole over the head and under the edge of the button in buttoned position and thereafter to move the other of said members to force the stock on the other side of the buttonhole over the head and under the edge of the button in buttoned position.

11. A buttoning machine having, in combination, means for positioning a button for

a buttoning operation, a pair of relatively movable tuckers, and mechanism operating to move one of said tuckers to carry one side of the buttonhole over the head of the button and crowd it against the eye of the button and thereafter to move the other of said tuckers to carry the other side of the buttonhole over the head of the button and crowd it against the eye of the button.

12. A buttoning machine having, in combination, means for holding a button, buttonhole fly engaging means constructed and arranged to dispose first one and then the other side of a buttonhole in buttoned position under the head of the button while the button is held stationary by said button holding means, and mechanism for operating said buttonhole fly engaging means.

13. A buttoning machine having, in combination, means for holding a button, a pair of relatively movable buttoning members, and mechanism for operating first one and then the other of said buttoning members to dispose of two sides of a buttonhole successively in buttoned position under the head of the button while said button is held stationary by said button holding means.

14. A buttoning machine having, in combination, means for positioning and holding a button for a buttoning operation, relatively movable buttoning members, and operating mechanism constructed and arranged to move said button positioning and holding means into position to hold the button, then to move one of said buttoning members to dispose one side of a buttonhole in buttoned position under the head of the button and thereafter to move the other of said buttoning members to dispose the other side of the buttonhole in buttoned position under the head of the button.

15. A buttoning machine having, in combination, button positioning means mounted for movement into operative position, buttoning members movable with said positioning means during said positioning movement and mounted for additional and relative movements to dispose first one and then the other side of a buttonhole in buttoned position under the head of the button, and mechanism for effecting said movements of said positioning means and buttoning members.

16. A buttoning machine having, in combination, a carrier, button positioning means mounted for movement with said carrier into position to engage a button, co-operating buttoning members movable with said carrier during said movement of said button positioning means and mounted for additional relative movements independently of said carrier to dispose one side of a buttonhole in buttoned position under the head of the button and with said carrier to dis-

pose the other side of said buttonhole under the head of the button, means for effecting said first named relative movement of the buttoning members, and means for operating said carrier.

17. A buttoning machine having, in combination, a reciprocating cross-head, button positioning and holding means mounted for movement with said cross-head into position to engage a button, coöperating buttoning members movable with said cross-head during said movement of said button positioning and holding means and mounted for additional relative movements first independently of said cross-head to dispose one side of a buttonhole in buttoned position under the head of the button and then with said cross-head to dispose the other side of said buttonhole under the head of the button, an auxiliary cross-head for effecting said first named relative movement of the buttoning members, and means for operating said cross-heads.

18. A buttoning machine having, in combination, a carrier, a buttoning member fixed to said carrier, a buttoning member mounted in said carrier for movement therewith and for additional movement relatively to said carrier, and mechanism constructed and arranged to operate said carrier and to effect an additional movement of said second named buttoning member relatively to said carrier and said first named buttoning member, said mechanism including means for causing the operative movements of the buttoning members to be effected against yielding resistance.

19. A buttoning machine having, in combination, a carrier, a buttoning member fixed to said carrier, a rod confined in said carrier for movement therewith and slidably mounted in said carrier for additional movement relatively to the carrier, a buttoning member fixed to said rod, means for operating said carrier, and means for moving said rod to operate said second named buttoning member relatively to said carrier and said first named buttoning member.

20. A buttoning machine having, in combination, a pair of buttoning members, operating mechanism for said buttoning members, and a member constructed and arranged to be rendered operative through movement of the buttoning members to effect a preliminary separation of the buttoning members to facilitate their operation.

21. A buttoning machine having, in combination, a pair of buttoning members, button positioning means including a member engaging said buttoning members and rendered operative through relative movement of said buttoning members and said other member to separate said buttoning members, and mechanism for relatively moving said

buttoning members and said positioning means to cause said buttoning members to be separated and a buttoning operation to be performed.

22. A buttoning machine having, in combination, a pair of buttoning members, mechanism constructed and arranged to operate first one and then the other of said buttoning members to carry the two sides of a buttonhole successively into buttoned position under the head of a button, and means operating to move the buttoning members successively toward the edge of the button head to facilitate carrying the sides of the buttonhole over said edge.

23. A buttoning machine having, in combination, a pair of buttoning members, means for holding a button including a button head positioning member engaging said buttoning members, and mechanism constructed and arranged to effect relative movement of the button and said button head positioning member to cause the said positioning member to engage the head of the button and thereafter to operate first one and then the other of said buttoning members to carry the two sides of a buttonhole successively into buttoned position under the head of said button, said button head positioning member operating during the buttoning movements of the buttoning members to move said buttoning members successively toward the edge of the button head to facilitate carrying the sides of the buttonhole over the edge of the button head.

24. In a buttoning machine, buttoning instrumentalities including a member having a cam face formed thereon, and a part having a cam path for the reception of said cam face to effect relative separating movement of said instrumentalities upon relative sliding movement of said part and said member.

25. In a buttoning machine, a pair of tuckers having cam faces on their inner sides, and a member between said tuckers in sliding contact therewith and having cam paths for the reception of said cam faces on the tuckers to wedge the tuckers apart for the purpose described upon relative movement of said member and said tuckers.

26. A buttoning machine having, in combination, means for positioning a button, buttoning members constructed and arranged to engage the two sides of a buttonhole at the edges thereof, mechanism for effecting relative movement of said button positioning means and said members to perform a buttoning operation, and means operating to prevent displacement of the buttoning members from the edges of the buttonhole during said relative movement.

27. A buttoning machine having, in combination, means for positioning a button,

- buttoning members constructed and arranged to engage the buttonhole edge binding stitches on the top face of a buttonhole fly at the two sides of a buttonhole, and mechanism for effecting relative movement of said button positioning means and said buttoning members to perform a buttoning operation, said buttoning members being formed to prevent displacement thereof
- 10 from the said edge binding stitches of the buttonhole during said relative movement.
28. A buttoning machine having, in combination, means for positioning a button, buttoning members constructed and arranged to engage the edge binding stitches on the two sides of a buttonhole, mechanism for relatively moving said button positioning means and said buttoning members to effect a buttoning operation including means
- 15 operating to separate said buttoning members to facilitate disposition of the sides of the buttonhole in buttoned position, and means for preventing displacement of the buttoning members from the edge binding
- 20 stitches of the buttonhole upon separation of the buttoning members.
- 25 29. A buttoning machine having, in combination, means for positioning a button, a pair of truckers constructed and arranged to engage the buttonhole edge binding stitches on the top face of a buttonhole fly at the two sides of a buttonhole, and mechanism for operating said truckers to carry the sides of the button hole outwardly to the
- 30 edge of the head of the button and force them over the said edge into buttoned position, said truckers being formed to prevent slipping from said edge binding stitches during their buttoning movement.
- 35 30. A buttoning machine having, in combination, button and buttonhole positioning means, truckers for engaging a buttonhole fly on the two sides of a buttonhole, and mechanism for effecting relative movement
- 40 of said positioning means and said truckers to effect a buttoning operation, each of said truckers having a work engaging face to bear on the buttonhole edge binding stitches on the top face of the buttonhole fly and a part to enter the buttonhole, said part being formed to facilitate its entrance into the buttonhole.
- 45 31. A buttoning machine having, in combination, button and buttonhole positioning means, truckers for engaging a buttonhole fly on the two sides of a buttonhole, and mechanism for operating said truckers to force the sides of the buttonhole over the head of a button to perform a buttoning operation, each of said truckers having a work engaging face to bear on the buttonhole edge binding stitches on the top face of the buttonhole fly and a buttonhole entering spur projecting beyond said face and
- 50 operating to maintain the trucker in engage-

ment with said edge binding stitches during the buttoning operation.

32. A buttoning machine having, in combination, button positioning means, buttoning members constructed and arranged to engage the buttonhole edge binding stitches on the top face of a buttonhole fly at the two sides of a buttonhole, and mechanism for effecting relative movement of said button positioning means and said buttoning members to effect a buttoning operation, said buttoning members having roughened work engaging faces for the purpose described.

33. In a buttoning machine, buttoning members each constructed for engagement with material adjacent to a buttonhole, each of said members comprising a shank part and a work engaging part pivoted to said shank part for swinging movement in a direction to carry the material outwardly toward the edge of a button head.

34. In a buttoning machine, buttoning members each constructed for engagement with material adjacent to a buttonhole, each of said members comprising a shank part and a work engaging part pivotally connected to permit said work engaging part to swing in a direction to carry the material outwardly toward the edge of a button head, and means for opposing yielding resistance to such swinging movement.

35. In a buttoning machine, relatively movable truckers each comprising a shank part and a work engaging part hinged to said shank part, and a spring pressing said work engaging parts toward each other.

36. A buttoning machine having, in combination, button positioning means, buttoning means comprising shank and work engaging parts pivotally connected, and mechanism for relatively moving said positioning means and said buttoning means to effect a buttoning operation.

37. A buttoning machine having, in combination, means for holding a button and positioning a buttonhole, buttoning members constructed and arranged to engage the stock at the side edges of the buttonhole and force the sides of the buttonhole to and over the edge of the head of the button and dispose them in buttoned position under the head of the button, each of said buttoning members comprising a shank part and a work engaging part pivoted to said shank part to prevent excessive strain upon said buttoning members during the buttoning operation thereof, spring means pressing said work engaging parts of the buttoning members inwardly from the edge of the button head, and mechanism for operating said buttoning members.

38. A buttoning machine having, in combination, means movable to seize the work and impart to it a positioning movement

transversely of the lengthwise edge of the work, mechanism for operating said means to cause it to seize the work and impart said positioning movement thereto, buttoning means, and mechanism for relatively moving said positioning means and said buttoning means to perform a buttoning operation.

39. A buttoning machine having, in combination, jaws constructed and arranged to seize material to which a button is attached and position said material, buttoning means and mechanism for relatively moving said jaws and said buttoning means to perform a buttoning operation with respect to the work.

40. A buttoning machine having, in combination, relatively movable jaws constructed and arranged to seize material to which a button is attached and impart a positioning movement thereto, buttoning means, and mechanism for operating said jaws and said buttoning means.

41. A buttoning machine having, in combination, button receiving means, means for seizing a button piece and drawing it inwardly to position a button in said button receiving means, buttoning means, and mechanism constructed and arranged to effect relative movement of said receiving means and said buttoning means to perform a buttoning operation.

42. A buttoning machine having, in combination, buttonhole fly receiving means, button receiving means, means for clamping a button piece movable to position a button in said button receiving means, buttoning means, and mechanism for relatively moving said receiving means and said buttoning means to perform a buttoning operation.

43. A buttoning machine having, in combination, buttoning means, a button receiving member, a pair of jaws for seizing a button piece and positioning a button in said button receiving member, and operating mechanism constructed and arranged to close said jaws upon the button piece and thereafter to effect relative movement of said buttoning means and said other parts to cause said buttoning means to take the work from the button receiving member and perform a buttoning operation.

44. A buttoning machine having, in combination, buttoning means, a pair of jaws for seizing a button piece, a forked member for receiving a button attached to said button piece, one of said jaws constituting an abutment to position a button in said receiving member by engagement with the eye of the button, and mechanism for relatively moving said buttoning means and said jaws to effect a buttoning operation.

45. A buttoning machine having, in combination, buttoning means, work receiving

means, jaws relatively movable in transverse relation to the plane of the work for gripping the work, said jaws being operatively connected to said receiving means for work positioning movement therewith, and mechanism for operating said receiving means and said buttoning means.

46. A buttoning machine having, in combination, buttonhole fly receiving means movable to position a buttonhole, button receiving means including button piece engaging jaws operatively connected to said buttonhole fly receiving means for movement therewith to effect a button positioning movement of a button piece, buttoning means, and mechanism for operating said fly receiving means and said buttoning means.

47. A buttoning machine having, in combination, buttonhole fly receiving means, a member for operating said buttonhole fly receiving means to position a buttonhole, button receiving means including button piece engaging jaws operatively connected to said member for movement therewith to effect a button positioning movement of the button piece, buttoning means, and mechanism for operating said buttoning means.

48. A buttoning machine having, in combination, buttoning means, work receiving means, relatively movable jaws constructed and arranged to be closed to seize and position the work upon movement of said work receiving means, and mechanism for operating said receiving means and said buttoning means.

49. A buttoning machine having, in combination, buttonhole fly receiving means movable to position a buttonhole, jaws for seizing a button piece and positioning a button, said jaws being constructed and arranged to be closed upon the button piece upon buttonhole positioning movement of said buttonhole fly receiving means, buttoning means, and mechanism for operating said fly receiving means and said buttoning means.

50. A buttoning machine having, in combination, buttonhole fly engaging means, button holding means, relatively movable button piece engaging jaws for positioning a button relatively to said holding means, said jaws and said holding means being constructed and arranged to cause said jaws to be closed upon relative movement of said jaws and said holding means, and mechanism for relatively moving said fly engaging means and said holding means to effect a buttoning operation.

51. A buttoning machine having, in combination, buttonhole fly engaging means, button holding means, jaws for seizing a button piece and positioning a button relatively to said holding means, a cam face on said holding means for automatically operating said jaws through sliding engagement

- of one of said jaws with said cam face, and mechanism constructed and arranged to effect relative movement of said fly engaging means and said holding means to effect a 5 buttoning operation.
52. A buttoning machine having, in combination, buttoning means, work positioning jaws comprising a relatively rigid jaw and a coöperating spring jaw, and mechanism 10 for relatively moving said jaws and said buttoning means to perform a buttoning operation.
53. A buttoning machine having, in combination, a pair of jaws for seizing a button piece, a forked member for receiving a button attached to said button piece, one of said 15 jaws constituting an abutment for the eye of said button, operating mechanism constructed and arranged to operate said jaws 20 to seize the button piece and effect a button positioning movement of the button piece relatively to said button receiving member, said jaws holding the eye of said button in engagement with said abutment jaw during 25 said movement to position said button in said receiving member, and means for thereafter performing a buttoning operation with respect to said button.
54. In a buttoning machine, a pair of 30 work gripping jaws, one of said jaws comprising a body portion and an abutment plate spaced from the body portion and the other of said jaws comprising a spring bar carrying at its ends transverse work engaging plates having their work engaging faces roughened to afford a firm grip upon the work.
55. In a buttoning machine, a pair of 40 work gripping jaws, one of said jaws having a depending projection, and a member operating through movement of the jaws relatively to said member to close said jaws through sliding engagement with said projection, the parts being constructed and arranged for adjustment to regulate the extent of closing movement of the jaws.
56. A buttoning machine having, in combination, means for performing a buttoning 45 operation, and a button receiving fork constructed and arranged to receive a button presented to the fork with its eye extending crosswise of the fork and longitudinally of the edge of the button piece and to turn said button as it is moved into the fork and position it with its eye lengthwise of the fork for presentation of the button to the buttoning means.
57. A buttoning machine having, in combination, means for performing a buttoning 50 operation, and a button receiving fork comprising two arms forming an open mouthed slot relatively wide at its mouth to receive a button with its eye extending crosswise of the slot and longitudinally of the edge of the button piece, said slot being narrower at

the back to position said button with its eye extending lengthwise of the slot for presentation to the buttoning means, the arms of the fork near the mouth of the slot being formed to turn said button as it is moved 70 into the fork to direct the eye of the button into the narrower portion of the slot.

58. A buttoning machine having, in combination, means for performing a buttoning operation, and a button receiving fork constructed and arranged to receive a button presented to the fork with its eye extending crosswise of the fork and longitudinally of the edge of the button piece, one arm of said fork having a cam face on its inner side to turn said button as it is moved into the fork and position it with its eye lengthwise of the fork for presentation of the button to the buttoning means.

59. A buttoning machine having, in combination, means for performing a buttoning operation, and a button receiving fork constructed and arranged to receive a button presented to the fork with its eye extending crosswise of the fork and longitudinally of the edge of the button piece, one arm of said fork being relatively straight and the other arm of the fork having its inner side curved near the mouth of the fork to turn said button as it is moved into the fork and position it in the fork with its eye lengthwise of the fork for presentation of the button to the buttoning means.

60. A buttoning machine having, in combination, a plurality of sets of operating instrumentalities, each comprising means for performing a buttoning operation and a button receiving fork constructed and arranged to receive a button presented to the fork with its eye extending crosswise of the fork, the outer arm of each of the forks on either side of the center set having its inner side formed to turn the button as it is moved into the fork and position it with its eye lengthwise of the fork for presentation to the buttoning means.

61. A buttoning machine having, in combination, a fork constructed and arranged to receive the eye of a button having its head resting upon the arms of the fork and having the inner sides of its arms obliquely beveled to prevent severing the button attaching thread, buttoning means, and mechanism for relatively moving said fork and said buttoning means to perform a buttoning operation.

62. A buttoning machine having, in combination, a fork comprising two arms forming an open mouthed slot to receive the eye of a button having its head resting upon said arms, said fork having a bevel 18 extending on the inner faces of said arms around said slot obliquely to the path of the button as it is moved into the fork to prevent severing the button attaching thread,

buttoning means, and mechanism for relatively moving said fork and said buttoning means to perform a buttoning operation.

63. A buttoning machine having, in combination, a button receiving fork comprising two arms forming a slot to receive the eye of a button having its head resting upon said arms, said arms having bevels 22 on their under sides forming gradual slopes extending from their outer ends a substantial distance longitudinally of the fork to facilitate straightening a button into an upright position to position it in said fork, buttoning means and mechanism for relatively moving said fork and said buttoning means to perform a buttoning operation.

64. A buttoning machine having, in combination, a button receiving fork, a pair of spring fingers carried by said fork to admit and yieldingly retain the eye of a button in the fork, said fingers having bevels 20 on their under sides to facilitate introducing the button into the fork in an upright position, buttoning means, and mechanism for relatively moving said fork and said buttoning means to perform a buttoning operation.

65. A buttoning machine having, in combination, buttoning means, means for operating the buttoning means including a movable carrier for said buttoning means, a device movable with said carrier to engage the head of a button, a member for supporting the eye of the button, and operating means for said member including a toggle constructed and arranged when straightened to move said member into button eye supporting position and afford a rigid support therefor against the thrust of the buttoning means.

66. A buttoning machine having, in combination, a plurality of button head engaging plungers, a corresponding number of button eye supporting anvils, carriers for the anvils, means for supporting said anvil carriers, a member detachably secured to said supporting means and extending over said anvil carriers to clamp them to said means, a plurality of sets of buttoning members, and mechanism for relatively moving said buttoning members and said other parts to position a plurality of buttons and perform buttoning operations with respect to said buttons.

67. A buttoning machine having, in combination, buttoning members, button holding means including a button head engaging plunger formed with its work engaging face cupped to receive and conform generally to the crown of the head of a button, said work engaging face having in its center an upstanding central projection from the crown of the button head, and mechanism for relatively moving said buttoning members and said

button holding means to hold a button and perform a buttoning operation.

68. A buttoning machine having, in combination, buttoning members, button holding means including a button head engaging plunger formed with its work engaging face cupped to receive and conform generally to the crown of the head of a button, a spring pressed plug forming part of said work engaging face, said plug normally projecting outwardly beyond the adjacent portions of said work engaging face and arranged to be pressed inwardly into the plane of or beyond said adjacent portions under pressure of the work, and mechanism for relatively moving said buttoning members and said button holding means to hold a button and perform a buttoning operation.

69. In a buttoning machine, a supporting sleeve, a plunger movable in said sleeve and having its upper end drilled and split, a nut threaded on said plunger end for adjustably determining the normal position of said plunger in said sleeve, and a tapered pin threaded through said nut and entering said plunger end, said pin operating to expand the walls of said plunger end against said nut to lock said nut on said plunger.

70. In a buttoning machine, work receiving members constructed and arranged to receive and position the work when the work is initially presented to the machine, supporting bars for said work receiving members, and means for securing said supporting bars in the machine constructed and arranged for movement to release said supporting bars simultaneously to permit the work receiving members to be removed from the machine.

71. In a buttoning machine, a plurality of work receiving members constructed and arranged to receive and position the work when the work is initially presented to the machine, supporting bars for said work receiving members, and means for securing said supporting bars in the machine including a part constructed and arranged for swinging movement to release said supporting bars and permit the removal of said work receiving members from the machine.

72. In a buttoning machine, a plurality of work receiving members, supporting bars for said work receiving members, a two part slide extending transversely of the machine and slotted lengthwise of the slide, and connections from said supporting bars to said slide constructed and arranged to permit free adjusting movement of said supporting bars lengthwise of said slide while securing said supporting bars to said slide for movement therewith, one of the parts of the slide being pivotally connected to the other part of the slide for swinging movement to release said supporting bars to permit the removal of the work receiving members from the machine.

73. In a buttoning machine, a plurality of work receiving members, supporting bars therefor, means for securing said supporting bars in the machine constructed and arranged to release said supporting bars simultaneously to permit removal of the work receiving members from the machine, a plurality of button eye supporting anvils, supporting bars for said anvils, means for securing the anvil supporting bars in the machine constructed and arranged to release said anvil supporting bars simultaneously to permit removal of the anvils from the machine, and a device constructed and arranged to operate both said means simultaneously.
74. A buttoning machine having, in combination, means for positioning a button constructed and arranged to hold said button against translation, buttonhole fly engaging means, and mechanism constructed and arranged to effect relative movement of said positioning means and said fly engaging means to cause the sides of a buttonhole to be disposed successively in buttoned relation to said button.
75. A buttoning machine having, in combination, means for positioning a button, relatively movable buttonhole fly engaging members, and mechanism constructed and arranged to effect relative movement of said positioning means and said fly engaging members, including relative movement of said fly engaging members, to cause the sides of a buttonhole to be disposed successively in buttoned relation to said button, to effect a buttoning operation, said positioning means being constructed and arranged to hold said button against translation during said buttoning operation.
76. A buttoning machine having, in combination, means designed to permit the presentation thereto of work provided with a plurality of buttons and buttonholes and constructed and arranged to dispose the two sides of each buttonhole successively in buttoned relation to the corresponding button to perform a plurality of complete buttoning operations with respect to said work, and mechanism for causing said means to perform buttoning operations substantially simultaneously.
77. A buttoning machine having, in combination, a plurality of sets of operating instrumentalities, each of said sets comprising means constructed and arranged to dispose the two sides of a buttonhole successively in buttoned relation to a button to perform a buttoning operation, and mechanism for operating said sets simultaneously to cause a plurality of buttoning operations to be effected at substantially the same time.
78. A buttoning machine having, in combination, a plurality of sets of operating instrumentalities, each of said sets comprising

means for positioning a button and relatively movable buttonhole fly engaging members, said means and said members being constructed and arranged for relative movement to dispose the two sides of a buttonhole in buttoned relation to a button to effect a buttoning operation, and mechanism for operating the several sets in such a manner as to cause a plurality of buttoning operations to be effected substantially simultaneously.

79. In a buttoning machine, means for positioning a button, and buttoning members for engaging the material on opposite sides of a buttonhole, each buttoning member being formed with a projection constructed and arranged to enter the buttonhole.

80. In a buttoning machine, means for positioning a button, buttoning members for engaging the material on opposite sides of a buttonhole, each buttoning member being formed with a projection constructed and arranged to enter the buttonhole, and means for moving each buttoning member toward the edge of the button after its projection has entered the buttonhole.

81. A buttoning machine having, in combination, means for positioning a button, buttonhole fly engaging means, and operating mechanism constructed and arranged to move said buttonhole fly engaging means to dispose the material at one side of a buttonhole below the edge of the button head and thereafter to dispose the material at the other side of the buttonhole below the edge of the button head.

82. A buttoning machine having, in combination, means for positioning a button, means for engaging a buttonhole fly adjacent to a buttonhole positioned over the head of said button, and mechanism for operating said buttonhole fly engaging means to cause the material of the buttonhole fly to be depressed relatively to said button head alternately at opposite sides of the buttonhole.

83. A buttoning machine having, in combination, means for positioning a button, a pair of relatively movable members arranged to engage a buttonhole fly respectively at opposite sides of a buttonhole positioned over the head of said button, and means for operating said members in succession to depress the material of the buttonhole fly relatively to said button head.

84. A buttoning machine having, in combination, means for positioning a button constructed and arranged to hold said button against translation, relatively movable members arranged to engage a buttonhole fly over the head of said button, and mechanism for operating said members to cause the material of the buttonhole fly to be depressed alternately at opposite sides of the button.

85. A buttoning machine having, in combination, means for holding a button against tipping movement, means for engaging a buttonhole fly at opposite sides of a buttonhole, and means for effecting relative movement of said button holding means and said buttonhole fly engaging means to render said fly engaging means effective successively at opposite sides of the buttonhole for disposing the material adjacent to the buttonhole in buttoned relation to the button while the button is thus held.
86. A buttoning machine having, in combination, means for holding a button against tipping movement, buttoning members arranged respectively for engagement with a buttonhole fly at opposite sides of a buttonhole, and means for operating said members in succession while the button is thus held.
87. A buttoning machine having, in combination, means for positioning a button, buttoning means constructed for engagement with the material at the edges of a buttonhole within the buttonhole, and means for effecting relative movement of said button positioning means and buttoning means to cause the buttonhole to be opened and a buttoning operation to be performed.
88. A buttoning machine having, in combination, means for positioning a button, buttoning means constructed for engagement with the material at the edges of a buttonhole within the buttonhole and also
- with the surface of the material at the sides of the buttonhole, and means for effecting relative movement of said button positioning means and buttoning means to cause the material at the sides of the buttonhole to be disposed in buttoned relation to the button.
89. In a buttoning machine, the combination with means for positioning a button, of buttoning means constructed to engage the material on opposite sides of a buttonhole, said buttoning means having portions shaped to project within the buttonhole.
90. In a buttoning machine, the combination with means for positioning a button, of buttonhole fly engaging means pivoted for swinging movement over the button head to force the material at the edge of a buttonhole outwardly toward the edge of the button.
91. In a buttoning machine, the combination with means for positioning a button, of buttonhole fly engaging members pivoted to swing respectively in opposite directions over the button head to carry the material at opposite sides of a buttonhole outwardly toward the edge of the button.

In testimony whereof I have signed my name to this specification in the presence of two subscribing witnesses.

HERBERT E. ENSLIN.
